UNITED STATES PATENT OFFICE.

AUGUST MACHA, OF CLEVELAND, OHIO, ASSIGNEE TO THE ELECTRIC CONTROLLER & MANUFACTURING COMPANY, OF CLEVELAND, OHIO, A CORPORATION OF OHIO.

APPARATUS FOR TREATING HOT-WIRE ELEMENTS FOR ELECTRICAL DEVICES.

Application filed December 9, 1922. Serial No. 695,948.

To all whom it may concern:

Be it known that I, AUGUST MACHA, a citizen of the United States, residing at Cleveland, in the county of Cuyahoga and State 5 of Ohio, have invented new and useful Improvements in Apparatus for Treating Hot-Wire Elements for Electrical Devices, of which the following is a specification.

My invention relates to apparatus for straightening and aging hot-wire elements for electrical devices. Hot-wire elements are used for many purposes, as to control the opening and closing of electric switches, to operate indicators of various kinds of electric meters, and the like. In such devices a length of wire having suitable electrical resistance is usually placed under a stretching strain in the circuit to be controlled or measured; and by its expansion a certain 15 distance due to its heating by the current flowing therein causes or permits an electric switch to open or an indicator to move in a certain direction, and by its contraction upon cooling to a definite degree to return 20 the switch to its closed position, or to move the indicator in the opposite direction. It has been found that wire untreated by my invention is more or less crooked, and that it stretches more or less after its incorporation 25 for use in electrical devices. It is the object of my invention to provide an apparatus and method for permanently removing the crookedness of such wires, and for stretching and heating such wire prior 30 to its economic use so as not only to eliminate its crookedness but also to cause it to elongate to such a degree and to readjust its internal structure in such a manner, as to give it a permanent set, whereby in economic use 35 to its economic use so as not only to eliminate its crookedness but also to cause it to elongate to such a degree and to readjust its internal structure in such a manner, as to give it a permanent set, whereby in economic use 40 its length will not materially change except in accordance with desired effects produced by heat due to the electric current therein. By my invention wire of definite or indefinite length may be prepared which have 45 definite characteristics resulting in reliable operations with little or no necessity for adjustments due to further straightening and aging of the wire.

The accompanying drawing shows a diagram of my invention applied to the treatment of definite length of wire.

On the drawing 1 designates a transformer core having the primary winding 2 and the secondary winding 3. The primary 55 winding 2 is connected by the wires 4 and 5,

the line switch 6 and the switch 7 to the alternating current supply lines 8 and 9. The switch has the movable contact 10 arranged to engage any one of the taps 11 taken at selected points on the winding 2. 60

12 is the wire to be treated for use as a hot-wire element. Its ends may be provided with the loops 13 and 14, the former being connected to one terminal of the winding 3 and surrounding the rod or bar 15, and the latter to the pin 16 carried by the lever 17 between its pivot 18 and its free end which is supplied with the pin 19 to receive the hook 20 supporting the pendent weight 21. The wire is thus put under a definite stretching strain dependent upon the mass of the weight 21, which is selected to produce such a strain on the wire 12 that it will, under the current supplied thereto, receive such characteristics as will prevent, during the 70 use for which it may be designed, any changes of length other than those due to its heating by the current therein.

22 is an overthrow switch designed for automatic interruption of the current in the 80 wire 12 when the wire has elongated a definite distance. It has the spring contact member 23 connected to the remaining terminal of the winding 3 and it has the movable member 24 pivoted at one end on the pin 25 and having its free end adapted to be engaged with, and disengaged from, the contact 23. The lever 17 and member 24 are connected together by the wire 32. 26 is a lever pivoted on the pin 27 and having 90 at its free end the fork members or fingers 28 and 29, between which the switch member 24 lies. The free end of the lever 17 lies above the lever 26 such a distance that, when the wire 12 has elongated a predetermined distance, the said end of the lever 17 will force the lever 26 downwardly until the finger 28 by engagement with the switch member 24 forces the latter downwardly 95 enough to cause the spring 30, having one end connected to an intermediate portion of the member 24 and the other end to the lever 26 between the members 28 and 29, to pass the pivot 25, at which time the spring 100 will throw the member 24 to the its dotted position against the stop 31, thereby opening the switch 22. In case the overthrow spring 30 fails to operate the switch, the continued lowering of the member 28 will 105 positively open the switch. The member 110

will throw the member 24 to the its dotted position against the stop 31, thereby opening the switch 22. In case the overthrow spring 30 fails to operate the switch, the continued lowering of the member 28 will 110 positively open the switch. The member 110

24 may be returned to its upper position by the lower finger 29 when the lever 26 is returned to its upper position, in which it may be retained by any suitable means 5 as by friction on the pin 27 or by other suitable device.

The switch 22 is useful for interrupting the current automatically when the treatment of the wire should terminate, but it 10 could be omitted, and the lever 17 or the weight 21 could operate an indicator or alarm in a well known manner, for apprising an attendant of the completion of the operation. After the opening of the switch 15 22 the wire 12 is allowed to cool under the strain of the weight 21, thus aging the wire, giving it a permanent condition for future use as a hot-wire element in electrical apparatus. The wire 12 in cooling contracts 20 and lifts the weight 21, but the contact 22 remains open until closed by the operator after the finished wire has been replaced by another to be treated. The amount of current to be transformed may be regulated 25 by the switch 7.

I claim—

1. In an apparatus for straightening or

aging hot-wire elements for electrical purposes, means for subjecting the wire to a predetermined stretching strain, means for 30 causing electric current to flow in the wire for heating the same, and means for interrupting the wire-heating current when the wire has elongated a definite distance.

2. In an apparatus for straightening or 35 aging hot-wire elements for electrical purposes, means for subjecting the wire to a predetermined stretching strain, means for causing electric current of predetermined value to flow in the wire for heating the 40 same, and means for interrupting the wire-heating current after the wire has elongated a definite distance.

3. In an apparatus for straightening or 45 aging hot-wire elements for electrical purposes, means for subjecting the wire to a predetermined stretching strain, means for causing electric current to flow in the wire for heating the same, and means for interrupting the wire-heating current when 50 the wire has received a predetermined set.

In testimony whereof I hereunto affix my signature this 5th day of December, 1922.

AUGUST MACHA.
